UNITED STATES PATENT OFFICE.

GEORGE SMITH, OF EAGLE GROVE, IOWA.

RAIL-RETAINER.

1,120,098.

Specification of Letters Patent.

Patented Dec. 8, 1914.

Application filed June 22, 1914. Serial No. 846,605.

To all whom it may concern:

Be it known that I, GEORGE SMITH, a citizen of the United States, residing at Eagle Grove, in the county of Wright and State of

5 Iowa, have invented certain new and useful Improvements in Rail-Retainers, of which the following is a specification, reference being had to the accompanying drawings.

This invention relates to new and useful 10 improvements in rail retainers and more particularly to what will be hereinafter known as a rail gage or anti-spreading device, the main object of the present invention being the provision of a device of this 15 character which can be quickly and readily placed in position for engagement with the outer flanges of the rails and prevent the rails from spreading and, at the same time, can be quickly and readily adjusted to securely fasten the same to the rails.

Another object of the present invention is the provision of means whereby the rail engaging members are securely held against rotary movement after being placed in position 20 so that they will not become disengaged from the flanges of the rails, during the tightening or fastening operation.

A further object of the present invention is the provision of a device of the above 25 character which will possess advantages in points of efficiency and durability, is inexpensive to manufacture and, at the same time, is simple in construction and operation.

30 With the above and other objects in view, the invention consists in the novel features of construction, combination and arrangement of parts as will be hereinafter referred to and more particularly pointed out in 35 the specification and claims.

In the accompanying drawing forming a part of this application, Figure 1 is a side elevation of a rail retainer constructed in accordance with my invention; and Fig. 2 45 is a top plan view, parts thereof being broken away and illustrated in cross section.

In carrying out my invention, I provide two like clamping members which include the spaced alined hook members 1, the parallel shank portions of which are integrally connected by means of a transverse bar 2, said bar being provided with a central opening 3 having formed in the side walls thereof the diametrically opposed transverse recesses 4, the purpose of which will be hereinafter more fully set forth. Removably

mounted within the openings 3 are the connecting rods 5, the outer ends of which are provided with suitable head members 6, while the inner ends thereof are threaded, 60 as shown at 7 and are movably engaged within the opposed ends of a turn buckle 8. From this it will be apparent that after the hook members have been engaged with the outer edges of the base flanges of the rails, 65 the turn buckle 8 may be readily rotated upon the inner ends of the rods 5 to securely fasten the clamping hooks in position.

70 Formed integral with the outer ends of the rods 5 and arranged upon opposite sides thereof, are the elongated lugs 9, the outer ends of which are formed integral with the head 6, said lugs being adapted to be arranged within the transverse recesses 75 4 when the rods 5 are in an operative position to prevent any turning movement of the transverse bar 2 upon the rods 5, so as to securely retain the hook members in position, that they may be readily engaged over 80 the base flanges of the rails.

From the above it will be apparent that the hook members 1 can be inserted beneath the rails between the ties and engaged with the outer base flanges of the rails, said 85 hooks being retained against rotary movement so that they may be readily engaged by means of the lugs 9 which are fitted within the recesses 4 to prevent said hook members from rotating, while attempting 90 to engage the same with the base flanges of the rails.

It will be readily apparent that my improved rail gage or anti-spreading device can be quickly and readily applied to the 95 railway rails in two different manners. The rods 5 may be engaged with the hook members and inserted beneath the rails from the outside thereof and then connected by the turn buckle 8, or the heads 3 may be 100 first connected by the turn buckle and the hook members pushed outwardly from the inner sides of the rails until they will engage with the base flanges after which the turn buckle 8 will be rotated to rigidly 105 clamp the hooks to the rail flanges.

From the above, it will be apparent that I have provided a simple and durable device which can not only be used as a rail gage, but can be used equally as well for 110 retaining the rails against spreading movement.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims.

10 Having thus described this invention, what I claim is:—

1. A device of the class described including alined hook members having spaced parallel shank portions, a transverse bar integrally connecting said hook members and having a central opening therein, removable rods arranged within said openings and having head portions to engage the transverse bars, means whereby to prevent 20 rotary movement of the hook members after being placed in position upon the rods, and a turn buckle connecting the inner ends of said rods, as and for the purpose set forth.

2. A device of the class described including spaced alined hook members having 25 parallel shanks, transverse bars integrally connecting said shanks, said bars each having a central opening provided with transverse recesses in the walls thereof, a removable rod arranged within said opening having a head adapted to engage the transverse bar, diametrically opposed lugs formed integral with the headed end of the rod and adapted to be arranged within said recesses to prevent rotary movement of the 35 bar upon the rod, and a turn buckle connecting the inner threaded ends of the rods from opposite sides of the track, as and for the purpose set forth.

In testimony whereof I hereunto affix my 40 signature in the presence of two witnesses.

GEORGE SMITH.
